UNITED STATES PATENT OFFICE.

RICHARD SWARTZ, OF PINE BLUFF, ARKANSAS.

DESIGN FOR A WARMING VESSEL.

SPECIFICATION forming part of Design No. 30,090, dated January 31, 1899.

Application filed December 19, 1898. Serial No. 699,776. Term of patent 7 years.

To all whom it may concern:

Be it known that I, RICHARD SWARTZ, a citizen of the United States, residing at Pine Bluff, in the county of Jefferson and State of Arkansas, have invented and produced a new and original Design for Warming Vessels; and I do hereby declare the following to be a full, clear, and exact description of the same, reference being had to the accompanying drawings, forming a part thereof.

Figure 1 is a plan view of my warming vessel, showing my new design. Fig. 2 is an edge view. Fig. 3 is a cross-sectional view on the line *x x* of Fig. 1.

As shown in the drawings, the leading or material feature of my design consists of a corrugated top wall 1, square-shaped except to its corners, which are a little rounded, said wall being provided with threaded opening 2 and a threaded stopper 3 and with a longitudinal convex depression 4, a bottom wall 5, parallel with the top wall in all its parts, except as to the corrugations and the depression 4, and side and end walls 6, which walls are crimped

or corrugated and flare out a little from the bottom wall up to the top wall.

Situated on the inside of the vessel and conforming to the curve thereof are A-shaped ribs 7, their apex resting against the inner face of the top wall and their feet against the inner face of the lower wall.

In face view the vessel is square, except its corners, which are a little rounded. In edge view it is circular, representing the arc of a circle.

The vessel is provided with a handle 10.

Having described my invention, what I claim as new, and desire to secure by Letters Patent, is—

The design for a warming vessel as herein shown and described.

In testimony whereof I affix my signature in presence of two witnesses.

RICHARD SWARTZ.
